CIRCULAR LOOM

Julio Izaguirre Villa and William Robertson MacEwan, Dundee, Scotland, assignors to The Weaving Machines Company, Limited, London, England

Application July 16, 1934, Serial No. 735,526
In Great Britain July 25, 1933

5 Claims. (Cl. 139—16)

This invention relates to circular looms of the type in which the warp shed is formed parallel with the axis of weaving or, in other words, lies substantially in a cylindrical surface co-axially 5 of said weaving axis; such a loom is described and claimed in the complete specification of the prior British Patent No. 336,246 and in United States Patent No. 1,860,975.

In a loom according to the British patent referred to, the warp threads pass in a direction substantially parallel with, or inclined at a comparatively small angle to, the central axis through a stationary reed-like annular frame, each radial cross member of which is formed with an undercut transverse recess in which a shuttle carrier is adapted to engage so as to be restrained positively to travel in a path determined by said recessed cross member, and a plurality of levers, pivoted intermediately of their lengths about 10 horizontal axes, extend each radially inwards from its pivot to engage in the groove of a cylindrical grooved cam concentric with the weaving axis, and radially outwards from the pivot to pass, as it is rocked about said pivot by the action of said cam, through the warp shed to co-operate with a shuttle or its carrier to impel the shuttle, and to bear subsequently against the deposited weft thread to beat-up said thread. In such a loom the cylindrical cam is, as a rule, 15 fast upon the central drive shaft by which also through the medium of cams or eccentrics the healds or heddle frames extending radially beneath the shuttle path are usually operated, as may also be operated means for maintaining the 20 tension of the warp threads substantially constant as the warp sheds are formed and reformed.

In the prior British specification No. 330,794 there is described and claimed improved mechanism for shuttle impelling and weft thread beating-up in a loom of the kind referred to, a plurality of substantially L-shaped members, mounted to move substantially vertically up and down in sequence, each substantially in the direction of its stem or upright limb, serving as a track for, and to impel, the shuttles, and each member carrying at its upper end a reed for spacing the warp and beating-up the weft threads.

50 The present invention has for an object to provide further improvements in that part of a loom, of the kind referred to, which serves for impelling the shuttles, beating-up the weft thread and maintaining proper spacing of the warp threads.

According to the invention the functions of shuttle impelling, on the one hand, and beating-up and warp thread spacing, on the other hand, are separated, the later function alone being served by a series of substantially rectangular, 5 rather than wedge or sector-shaped, reed members moved up and down by a cylindrical cam; and, in the wedge or sector-shaped spaces between the outer portions of adjacent reed members is disposed a plurality of fixed members constituting a track for an arcuate shuttle carrier and a series of rotary driving members which come successively into driving co-operation with the shuttle carrier and so impel it uninterruptedly around the track. 10

Preferably, the shuttle carrier is formed with rack teeth at its outer or inner margin and the rotary driving members are in the form of pinions each with a vertical drive shaft extending downwardly therefrom to be in turn driven 15 at its lower end, by spur gearing or equivalent, from a central drive shaft by which the cylindrical cam is driven and the healds or heddle frames are operated.

One form of the invention as applied to a two 20 shuttle loom of the kind referred to, having means for operating the healds or heddle frames according to the prior British Patent No. 392,068 and means for maintaining constant the tension of the warp threads according to prior British Patent No. 380,793, and United States Patent No. 1,949,571 is illustrated by the accompanying drawings; of which,

Figure 1 is a view showing the relevant parts of a loom in sectional elevation on the line 1—1 of Figure 2;

Figure 2 is a fragmentary sectional plan view on the line 2—2 of Figure 1; and,

Figure 3 is a diagrammatic "development", not to scale, showing the positions occupied by the 40 reed-members and the shuttles, around the circle 3—3 of Figure 2; whilst,

Figures 4 and 5 are fragmentary views drawn to an enlarged scale showing a detail in side and in end elevation, respectively.

As shown, a fixed upright shaft 11 co-axial with the central axis of weaving has rotatable therearound a tubular drive shaft 12 from which the moving parts of the loom derive their motion. Each warp thread, of which two are indicated by broken lines, passes upwardly from a warp beam (not shown) through a fixed distributing ring 13, within a flexible but non-extensible warp tensioning hoop 14, over a fixed ring 15 by which the "bottom" of the shed is 50 55

determined, through an eye, e. g., 16, of a heald, and, within a second fixed ring 17 determining the "top" of the shed, and thence to the usual web receiving beam (not shown).

5 The warp tensioning means employed are in accordance with prior British Patent No. 380,-
793 and United States Pat. No. 1,949,571 and comprise simply the flexible ring 14 of more
10 or less springy material which encircles the central axis of weaving and is of such dimension
as to bear radially upon all the warp threads
and to be distorted out of its natural circular
form by the varying pressure of said threads
thereon as the sheds are formed and reformed;
15 said ring 14 being free to move at all points
radially inwards and outwards from the central
axis of weaving but restrained against axial
motion.

The operation of the heddle frames of the
20 loom, which are indicated at 18 (see particularly Figure 2) and are disposed in a series of
upper and lower pairs uniformly around the
axis of weaving, is in accordance with prior
British Patent No. 392,068 and comprises a
25 single cam 19 fast on the tubular drive shaft
12 and having at its upper face an eccentric
groove 20, and for each pair of upper and lower
30 heddle frames 18 a corresponding pair of upper
and lower racks 21 and 22; each lower rack
35 22 having a downward extension 23 which is
slidable on a rectangular section radial guide
rod 24 and carries a roller 25 which co-operates
as a "follower" with the groove 20 of the cam
19, whilst motion is transmitted from the lower
35 rack 22 to the corresponding upper rack 21
through the medium of a pinion 26.

The tubular drive shaft 12 also has fast
thereon a cylindrical cam 27 with the track 28
40 of which co-operate the rollers 29 of a series
of slides 30 which are moved upwardly and al-
lowed to move downwardly each on a pair of
45 guide rods 31 by the cam 27 and, being equal
in number to the number of pairs of upper and
lower heddle frames 18, carry each a reed mem-
ber 32 which (see Figure 2) is substantially
50 rectangular in shape so that between each reed
member 32 and its neighbour there is left clear
a sector-shaped space. From their inner ends,
however, (see Figure 2) the blades of each reed
55 member 32 extend radially of the central axis
to points therein just outside the diameter of
the top of the warp shed. A series of fixed
shuttle track members 33, each of which has
60 a deeply undercut shoulder 34 at its inner end,
is accommodated in the sector-shaped spaces
between the reed members 32, and the shuttle,
indicated by broken lines at 35, is mounted de-
65 tachably upon an arcuate carrier 36, the outer
margin of which is toothed and which is formed
near its outer margin with an upstanding flange
70 37. It will be seen from Figure 2 of the draw-
ings that this shuttle carrier 36 is substantially
equal in length to the distance measured
75 around the shuttle track between one track
member 33 and the next track member 33 but
two, so that without any interference with either
the reed members 32 or the movement of the
warp threads during shedding, the shuttle 35 is
80 at all times amply supported throughout its
travel around the shuttle track. The tubular
drive shaft 12 has also fast thereon a large
diameter spur wheel 38, the teeth of which mesh
85 with a series of pinions 39 fast upon the lower
ends of a plurality of vertical drive shafts 40
90 equal in number to the shuttle track members
75

33 and each of which has fast upon its upper
end a pinion 41 with which is formed integrally
95 a flange 42, the diameter of which is so much
greater than the overall diameter of the teeth
thereof as will enable the co-operation of the
flange 37 of the shuttle carrier 36 with the
100 flanges 42 of said pinion 41 to ensure free
meshing of the teeth of said carrier 36 with
those of successive pinions 41, despite the out-
ward thrust of the carrier 36 on said pinions 10
41 due to centrifugal force as a shuttle 35 is
105 impelled around its track by the means de-
scribed. It will be seen that the pinions 41
with their integral flanges 42 serve not only for
connecting the shuttle 35 with the drive there-
110 of but also as rollers against which the shuttle
runs; it being important that the centrifugal
force of the shuttle should be taken by means
which introduce but little friction, especially
115 where it is desired, as is usual, to run the loom
at high speed. In this connection, it has been
found possible to run a loom as described at a
speed so high as one hundred revolutions per
120 minute without any ill effect upon the quality of
the web produced or upon reliability of opera-
tion.

In the case, for example, of a large loom mak-
ing broad cloth, a shuttle carrier may be formed
at its inner margin with rack teeth for co-oper-
ation with the drive pinion, rollers or other
means being provided for co-operation with the
outer margin of the carrier to resist the out-
ward thrust of the shuttle.

It will be seen that by the present invention
an efficient drive for the shuttle is provided and
35 that, at the same time, proper warp thread spac-
ing is maintained by the reed members 32; it
being impossible for even a single warp thread
40 to shift out of its proper place because it re-
mains always between two blades of a reed mem-
ber. From Figure 3 of the drawings it will be
45 clear that although the reed members pass
successively beneath the shuttles and their car-
riers they nevertheless do not at any time come
into contact with either a shuttle or its carrier,
50 their up and down movement being solely for the
purpose of beating-up the weft threads, as in-
dicated at 43 in that figure.

Each weft thread 43 (see Figures 4 and 5)
55 passes as it leaves the corresponding shuttle 35
through an eye 44 of a trip-member 45 and so
maintains the latter elevated about a pivot 46
on the shuttle carrier 36 to an extent determined
60 by a stop 47. The shuttle carrier 36 is formed
with an opening 48 through which the trip-mem-
ber 45 projects, when not maintained elevated,
65 as in the event of breakage of the weft thread
43, as shown in broken lines in Figure 4. The
shuttle track members 33 are grooved, as in-
70 dicated at 49, across their upper faces to give pas-
sage to the lowered trip-member 45 and in the
case of at least one track member 33 there ex-
75 tends vertically therethrough from the groove 49
a guideway for a control rod 50 supported by a
rocking lever 51 to which it is pivotally attached
80 at its lower end. The lever 51 is pivoted, as in-
dicated at 52, on a fixed part of the loom and is
coupled with means (not shown) for controlling
85 the operation of the loom. Normally the upper
end of the control rod 50 lies in the path of the
trip-member 45; the arrangement being such
90 that when a weft thread 43 breaks and the trip-
member 45 drops it will depress the control rod
95 50, shift the rocking lever 51 correspondingly and
so bring about such action (e. g., under spring
75

influence) of the means for controlling the operation of the loom as will cause the latter to stop. It will be seen that in this way trouble resulting from breakage of a weft thread is reduced to a minimum.

5 What we claim is:

1. In a circular loom of the type wherein the warp shed is formed substantially parallel with the axis of weaving, a driving means substantially coaxial with the central axis of weaving, reed members having their inner ends substantially radial with respect to the axis of weaving, and projected beyond the radial portions in substantially parallel relation to provide divergent 10 spaces between adjacent reeds outwardly of the radial portions thereof, shuttle carrier supports mounted in said spaces, a shuttle carrier guided by said supports, cooperating means on the shuttle carrier and on said supports to compel 15 constant uniform movement of the shuttle carrier, and means for operating the reeds toward and from a plane below the plane of movement of the shuttle carrier to a plane substantially coincident with the top of the warp shed for beating 20 up, the reeds maintaining accurate spacing of 25 the warp threads at all times.

2. A construction as defined in claim 1, wherein the shuttle carrier is designated to simultaneously cooperate with a plurality of supports, 30 and wherein the supports are formed to prevent movement of the carrier beyond its operating plane.

3. A construction as defined in claim 1, wherein the cooperating means on the supports and 35 shuttle carrier for operating the latter include a pinion on the supports and teeth on the edge of the carrier, the pinion and carrier being

formed to provide a roller bearing for the carrier.

4. A construction as defined in claim 1, wherein the cooperating means on the supports and on the shuttle carrier for operating the latter 5 include a driven pinion on the support and cooperating teeth on the carrier, the pinion being provided with a disk and the adjacent edge of the carrier being formed with a projection to bear against the edge of the disk to provide a roller 10 bearing for the carrier, with the edge of the carrier underlying the disk to prevent upward movement of the carrier in operation.

5. In a circular loom of the type referred to, a driving means centrally coaxial with the central axis of weaving, reed members substantially rectangular in plan disposed about the axis of weaving, the form of the reed members defining sector-shaped spaces between adjacent reed members, mechanism operated by the driving 15 means for reciprocating the reed members, track supports arranged in the sector-shaped spaces 20 between the reed members, a shuttle carrier mounted on and movable relative to said supports, means operated from the driving means for 25 driving the shuttle carrier, a trip member mounted on the shuttle carrier, and a loom operating control member arranged beneath the shuttle carrier, said trip member cooperating with the weft thread of the shuttle to maintain 30 the trip member out of the path of the control member while the weft thread is intact, the breakage of the weft thread permitting the trip member to be moved into the path of the control member for the control of the loom. 35

JULIO IZAGUIRRE VILLA.
